UNITED STATES PATENT OFFICE.

CASPER D. MEALS, OF TRENTON, NEW JERSEY, ASSIGNOR TO READING STEEL CASTING COMPANY, OF READING, PENNSYLVANIA, A CORPORATION OF NEW JERSEY.

LIFTING-CLAMP.

1,351,530.

Specification of Letters Patent. Patented Aug. 31, 1920.

Application filed September 16, 1919. Serial No. 324,103.

To all whom it may concern:

Be it known that I, CASPER D. MEALS, a citizen of the United States, and a resident of Trenton, in the county of Mercer and State of New Jersey, have made and invented certain new and useful Improvements in Lifting-Clamps, of which the following is a specification.

My invention relates to improvements in clamps, the object being to provide a clamp which is so constructed and arranged that plates of varying thicknesses can be successfully handled, the clamp automatically adapting itself to the thickness of the plates being handled and then positively gripping the same. The invention comprehends a construction which may be employed with equal facility to both horizontal and vertical lifting clamps.

A further object of the invention is to provide a lifting clamp which can be manually adjusted so as to clamp and grip plates of a different class or degree of thickness and accomplish all of the aforementioned ends in a clamp which is inherently rugged, of simple design, and comparatively few working parts.

Other objects and advantages will appear as the description proceeds, wherein it is to be understood that changes in the precise embodiment of the invention may be made within the scope of what is claimed without departing from the spirit thereof.

In the accompanying drawings:

35 Figure 1 is a view in side elevation of my novel clamp, various positions of the clamping lever being illustrated in dotted lines;

Fig. 2 is a front view in elevation thereof;

Fig. 3 is a view in section taken on the line 3—3 of Fig. 2;

Fig. 4 is a detail view of the eccentric fulcrum or pin mounting of the clamping lever taken on the line 4—4 of Fig. 3.

Fig. 5 is a view in side elevation of a modified or developed form of my lifting clamp;

Fig. 6 is a view in front elevation thereof, portions of the clamp being broken away, illustrating the details of construction;

50 Fig. 7 is a detail view of the lower end of the clamping lever; and

Fig. 8 is a view in side elevation of a vertical clamp embodying the characteristic features of my invention.

55 Referring now to the several views, my

improved clamp is formed with a main frame 11, the same being generally U-shape in that it is formed with the overhanging arms 12—13 which are connected at one extremity by the cross-piece 14. The arm 12 is formed so as to receive thereagainst the plates or other articles 15 which are to be lifted or handled, and in effect constitutes an abutment, while the overhanging arm 13 is provided with an opening 16 to which a clamping lever 17 is pivoted.

The clamping lever is formed of the two side sections 18—18, portions of the same being bent in opposite directions so as to form the slot 19 in which the supporting arm 13 of the clamping frame is received. The sections 18—18 are held together so as to form an integral construction by the rivets or other fastening means 20. In this connection, note is made that the arm 13 is reduced in thickness at its upper extremity so as to reduce the required size of the slot 19, thus lightening the entire clamp without detracting from its strength. The upper extremity of the lever is provided with the opening 21 for the reception of a shackle or chain which is connected to a lifting crane or other device, while the lower end of the lever is provided with the cam face 22, the same being a developed eccentric curve taken in connection with pivot receiving openings 23, with which the clamping lever is provided.

In order to materially increase the range of adjustment or action of the clamp and at the same time not in any way prevent the efficient gripping action thereof, I provide an eccentric pin 24, the same being formed with a cylindrical body 25 which rotates within the pivotal opening 16 in the overhanging arm 13 of the clamp frame. Projecting to each side of the cylindrical body 25 are the eccentric lugs or trunnions 26 which fit within the openings 23 of the clamping lever and are fastened thereto by the keys 27, the effect of such construction being that as the clamping lever 17 is rotated or moved by the action of the hoisting chain, the turning movement thereof will be imparted to the eccentric pivot 24 and through the action of the keys 27 and the trunnions 26 the cylindrical body 25 will be rotated in the opening 16 and the trunnions 26 will be accordingly raised or lowered with relation to the abutment portion 12 of

the clamping frame, according to the direction of rotation of the clamping lever. From the foregoing it will be apparent that the clamp automatically adjusts itself to the 5 class or species of plates being handled; the rotation of the clamping lever moving the cam end thereof into engagement with a plate and causing the rigid and efficient gripping of the plate between the cam lever 10 and the opposite abutment.

In assembling the clamping lever to the frame the eccentric pivot 24 is first inserted so that the cylindrical portion 25 is located within the opening 16 in the clamp frame. 15 The two side sections of the clamping lever are then brought together so that the trunnions 26 project within the openings 23 in said sections and are so secured by the lugs 27. The two sections are then permanently 20 secured or fastened together by the rivets 20 or other suitable fastening means.

For those instances where a very large variation in the size of the plates or articles to be handled is met with, I provide the arrangement as disclosed in Figs. 5 and 6, wherein the trunnions 26 of the pivot pin are not keyed directly to the side sections 18 of the clamping arms but are continued therethrough and are keyed to the indexing plates 28; these indexing plates being provided with the oppositely located openings 29 which are adapted to be engaged by the latches 30, the same being normally held in engagement therewith by the springs 31, 35 although it will be readily understood that any equivalent means for holding the indexing plates in position may be utilized. The openings or indexing points 29 being located at 180° apart and the plates being rigidly 40 keyed to the trunnions 26 of the pivot pin, provide that the trunnions may be held in either a raised or lowered position. Thus when it is desired to clamp and grip plates which are relatively thick, the indexing plates 45 28 are turned so that the trunnions 26 lie above the axis of the cylindrical portion of the eccentric pivot, which position of the trunnions causes the clamping lever to be raised and allows the cam face 22 of the 50 clamping lever to engage and grip relatively thick plates. In a similar manner, when it is desired to operate the clamp with relatively thin plates, the latches 30 are moved inwardly and the indexing points 29 turned 55 through 180° , which causes the lowering of the trunnions 26 and corresponding lowering or moving of the clamping lever 17 toward the abutment portion 12 of the frame; it being understood that should it be so desired the plates 28 may be provided with additional indexing points.

The clamps above described are for the handling of horizontal plates and accordingly are known as horizontal clamps. My 65 invention, however, may be applied with

equal facility to vertical clamps such as illustrated in Fig. 8, wherein the clamp is formed with the frame 35 which is composed of the overhanging arms 36-37, the arm 36 forming the abutment and may be provided with the serrated face 38, while the arm 37 is provided with the pivot-receiving opening 39 in which extends the cylindrical portion 40 of the eccentric pivot. The eccentric pivot is formed in the manner previously described and includes the cylindrical portion 40 and the projecting eccentric trunnions 41, the latter being keyed to, so as to be rotated by, the clamping lever 42. The clamping lever 42 is formed with two side 80 sections permanently secured together by rivets or other fastening means 43, the sections being assembled upon the eccentric pivot after the latter has been assembled in the opening 39 in the clamp frame; the 85 clamping lever in this instance extending over and across the clamp frame and provided with the opening 44 for the reception of the chain or shackle by which the clamp is secured to the hoisting chain. The opposite extremity of the clamping lever is provided with the cam face 45 which is thrust into wedged engagement with the plate and forces the same against the opposite abutment of the frame and accordingly grips the 90 same when upward pressure is brought to bear upon the clamping lever.

Having thus described and explained my invention, I claim and desire to secure by Letters Patent:

1. A lifting clamp comprising a frame composed of connected overhanging arms, the one arm being formed as an abutment and the opposite arm reduced in thickness and provided with a pivot opening extending therethrough, a clamping lever composed of two side sections forming a slot therebetween receiving the reduced arm within said slot, a pivot pin engaging openings provided in the side sections of said 110 clamping lever and within the arm of the frame, the lower extremity of the clamping lever provided with a cam face and the opposite extremity of the lever provided with means for securing it to a lifting member. 115

2. A device of the class described comprising an abutment and a supporting arm held in fixed relation thereto, a clamping member, and an eccentric pivot rotatably secured to said supporting arm and fixedly 120 secured to said clamping member so as to be rotated thereby and for the movement of said clamping member toward and away from said abutment.

3. A lifting clamp comprising a frame 125 one portion of which constitutes an abutment and another portion constituting a supporting arm, a clamping lever with the one extremity thereof having a cam face adapted to coöperate with the abutment of 130

- the frame, and an eccentric pivot member extending within openings within the supporting arm and the clamping lever, said eccentric pivot rotatably connected to the one and 5 fixedly connected to the other of said members whereby the rotation of the clamping lever with relation to the frame moves the cam face thereof toward and away from the abutment of said frame.
- 10 4. A lifting clamp comprising a frame including an abutment and an overhanging arm, a clamping lever provided with a cam face coöperating with the abutment for the gripping of articles, the remote extremity 15 of the clamping lever adapted to be rotated when a lifting force is applied to the clamp, and an eccentric pivot formed with a cylindrical portion rotatably engaging the overhanging arm of the clamp frame and eccentric 20 trunnions projecting from the cylindrical portion engaging the said clamping lever adapted to support the same and to move the clamping lever toward and away from the abutment of the frame upon the 25 rotation of said clamping lever.
5. A lifting or holding clamp comprising a frame one portion of which is formed as an abutment and the other portion as an overhanging arm, said arm being provided 30 with an opening therein, a clamping lever provided with a cam face adapted to co-operate with the abutment for the gripping of articles, means whereby said clamp lever will be rotated upon the application of a 35 lifting force, said clamping lever formed of two side sections with portions thereof bent in opposite directions to form a slot, receiving the overhanging arm of the frame therein, means for securing the side sections of the clamping lever together, and an eccentric pivot having a cylindrical portion rotatably engaging and fitting within the opening in the arm of the frame, trunnions projecting from the central cylindrical portion of said pivot and eccentric thereto, said trunnions projecting within openings formed in the side sections of said clamping lever, and means whereby said trunnions are rotated by the rotation of said 45 50 clamping lever.
6. In an apparatus of the class described, a frame having an abutment and an overhanging arm, a clamping member, and an eccentric pivot rotatably engaging the overhanging arm with the eccentric portions of said eccentric pivot extending through openings formed in said clamping arm, and means whereby the position of the said eccentric pivot may be adjusted for given po-
- sitions of said clamping lever and held in 60 adjusted positions.
7. An adjustable clamp comprising a frame including an abutment and an overhanging arm, a pivot having a cylindrical portion engaging said arm, eccentric trunnions projecting from said cylindrical portion, a clamping lever mounted upon said eccentric trunnions, and means for locking said trunnions to said clamping lever in adjusted positions. 70
8. An adjustable clamp comprising a frame including an abutment and an overhanging arm, a pivot having a cylindrical portion engaging said arm, eccentric trunnions projecting from said cylindrical portion, a clamping lever mounted upon said eccentric trunnions, and means for locking said trunnions to said clamping lever in adjusted positions, said clamping lever being provided with a cam face. 75
9. An apparatus of the class described comprising a frame including an abutment and an overhanging arm, a pivot rotatably engaging and mounted within an opening within said arm, said pivot provided with eccentric trunnions projecting therefrom, a clamping lever provided with openings therein receiving the said trunnions therethrough, means whereby the application of a lifting force tends to rotate said clamping 80 85 lever, indexing plates secured to said trunnions, and means mounted upon said clamping lever adapted to hold said indexing plates in adjusted positions.
10. An apparatus of the class described comprising a frame including an abutment and an overhanging arm, a pivot rotatably engaging and mounted within an opening within said arm, said pivot provided with eccentric trunnions projecting therefrom, a clamping lever provided with openings therein receiving the said trunnions therethrough, means whereby the application of a lifting force tends to rotate said clamping 90 95 lever, indexing plates secured to said trunnions, and means mounted upon said clamping lever adapted to hold said indexing plates in adjusted positions.
11. An apparatus of the class described comprising a frame including an abutment and an overhanging arm, a pivot rotatably engaging and mounted within an opening within said arm, said pivot provided with eccentric trunnions projecting therefrom, a clamping lever provided with openings therein receiving the said trunnions therethrough, means whereby the application of a lifting force tends to rotate said clamping 100 105 lever, indexing plates secured to said trunnions, and means mounted upon said clamping lever adapted to hold said indexing plates in adjusted positions, the lower end of said clamping lever provided with a cam face. 110

Signed at Trenton, in the county of Mercer and State of New Jersey, this 12th day of September A. D. 1919.
